A. CODDING, JR., OF NORTH ATTLEBOROUGH, MASSACHUSETTS.

Design No. 3,383, dated February 23, 1869.

DESIGN FOR A BRACELET.

The Schedule referred to in these Letters Patent and making part of the same.

To all whom it may concern:

Be it known that I, A. CODDING, Jr., of North Attleborough, Bristol county, Massachusetts, have invented a new and original Design for Bracelet; and I do hereby declare that the following is a full, clear, and exact description thereof, which will enable others skilled in the art to make and use the same, reference being had to the accompanying drawing, forming a part of this specification.

This design comprises the configuration and combination of color and form, as shown in the drawing, which latter is a perspective view of a bracelet formed after the said design.

A is the internal mounting, of gold, or a semblance of gold, and the external fillet, of jet, or a semblance of jet.

aa are plates, at the junction of the two halves of the bracelet, the said halves being drawn together by

two elastic straps, concealed within the body of the bracelet, in the usual manner.

The external view of the design exhibits the jet fillet, having borders of gold, or a semblance thereof, which is occasioned by slightly overlapping the edges of the jet-material with the edges of the internal mounting A, as shown.

Having thus described my invention,

What I claim as new, and desire to secure by Letters Patent, is—

The design or pattern for bracelets herein set forth.

The above specification of my invention signed by me, this 19th day of October 1868.

A. CODDING, JR.
